UNITED STATES PATENT OFFICE.

MINOTT A. O. STILSON, OF WATERBURY, CONNECTICUT.

RAILWAY-TIE.

1,037,559.

Specification of Letters Patent.

Patented Sept. 3, 1912.

Application filed February 21, 1912. Serial No. 679,039.

To all whom it may concern:

Be it known that I, MINOTT A. O. STILSON, a citizen of the United States, residing at Waterbury, in the county of New Haven and State of Connecticut, have invented a new and useful Improvement in Railway-Ties; and I do hereby declare the following, when taken in connection with the accompanying drawings and the characters of reference marked thereon, to be a full, clear, and exact description of the same, and which said drawings constitute part of this application, and represent, in—

Figure 1 a top or plan view of a railway tie constructed in accordance with my invention, shown with rails resting thereon. Fig. 2 a side view of the same. Fig. 3 a longitudinal sectional view of one end of the tie. Fig. 4 a perspective view of one 20 of the wooden blocks detached.

This invention relates to an improvement in railway ties, and particularly to ties made of reinforced concrete, the object of the invention being to construct a tie which will 25 be sufficiently strong to stand the necessary strain and which shall contain wooden blocks to which the rails are secured, which blocks may be removed, if necessary, when worn out; and the invention consists in the 30 construction hereinafter described and particularly recited in the claims.

In constructing ties in accordance with my invention, I locate wooden blocks 2 and 3 in a suitable mold by which they are firmly 35 held. These blocks are rectangular in transverse section with side walls tapered inward from their lower edges to the top. These blocks are of sufficient depth to receive an ordinary rail spike, and the blocks are preferably bored with four holes 4 to receive a 40 such spikes. As a rule, however, only two spikes are used at each tie, but by providing a block with four holes provision is made for shifting the spikes from one hole to another. 45 These blocks are treated with any suitable wood preservative and the holes bored in the block assist in allowing the preservative to saturate the block. Preferably the main grain of the wood block will run parallel 50 with the length of the tie, but it is obvious that instead of employing wood blocks, wood fiber or other material may be employed with equal success. The molds in which the tie is formed are provided with 55 recesses in each side to form projections 6 and 7 on each side and also extensions 8

below the bottom of the main portion of the tie. The upper edges of the projections 6 and 7 are in line with the lower faces of the blocks 2 and 3. These projections and extensions assist in holding the tie more firmly in place in the roadbed and provide a rigid bearing for the blocks. Extending longitudinally of the tie and near the bottom thereof, is what I will term the main 65 reinforce 9 provided with depressed portions 10 where it passes beneath the wooden blocks 2 and 3. Surrounding the two sides and bottom of each block is an auxiliary reinforce 11. These reinforces are preferably 70 formed from scrap perforated metal, although any other material may be employed. The portion 12 of the auxiliary reinforce 11 passing below the blocks is preferably laced or tied to the portion 10 75 of the main reinforce 9. In forming the tie these reinforces may be supported by spikes 14 driven at an angle through the upper portions of the reinforce 11 and into the wooden blocks as shown in Fig. 3 of the 80 drawings. In this way the reinforces are held in proper position with relation to the blocks until the mold has been filled with concrete and the concrete has set. I may here state that preferably in the mixture 85 of concrete I will employ cinders, and in this way a lighter tie is produced. When the tie is completed, the spikes 14 may be withdrawn if desired, although they will serve to hold the blocks in the tie. The 90 bases 15 of the rails 16 rest upon the blocks 2 and 3 and are secured by spikes 17 entering the holes 4 prepared for them. When it is desired to adjust the tie or insert new blocks, it is only necessary to remove the 95 spikes 17 and drive the blocks out of the tie and insert new blocks therein. The projections below the block provide a sufficient thickness of concrete below the blocks to properly support them and give requisite 100 strength to the ties at these points.

It will be understood that the number of blocks in the tie may be more or less according to the purposes for which the tie is to be used, and the number of holes may also 105 be varied.

I claim:—

1. A tie comprising wooden blocks having tapered sides, said blocks located in a concrete body which body between its ends 110 is formed with projections on opposite sides of but below said blocks beyond the ends of

- which they project, a main reinforce strip extending longitudinally of the tie and formed with bends below the blocks, and auxiliary reinforces surrounding the sides and bottoms of the said blocks.
5. 2. A tie comprising wooden blocks having tapered sides, said blocks located in a concrete body which body between its ends is formed with projections on opposite sides of but below said blocks beyond the ends of which they project, a main reinforce strip extending longitudinally of the tie and formed with bends below the blocks, auxiliary reinforces surrounding the sides and bottoms of the said blocks, and spikes extending diagonally through the auxiliary reinforce and into the said blocks.
10. 3. A tie comprising wooden blocks hav-
- ing tapered sides, said blocks located in a concrete body formed with projections on opposite sides of but below said blocks beyond the ends of which they project, a main reinforcing strip extending longitudinally of the tie and formed with bends below the blocks, an auxiliary reinforce surrounding the sides and bottoms of said blocks, said auxiliary and main reinforces laced together below the said blocks.
15. In testimony whereof, I have signed this specification in the presence of two sub-
scribing witnesses.

MINOTT A. O. STILSON.
